UNITED STATES PATENT OFFICE.

CHARLES HENKEL, OF FORT WAYNE, INDIANA.

FENCE-POST.

1,283,178.

Specification of Letters Patent.

Patented Oct. 29, 1918.

Application filed May 23, 1917. Serial No. 170,475.

To all whom it may concern:

Be it known that I, CHARLES HENKEL, a citizen of the United States, residing at Fort Wayne, in the county of Allen and 5 State of Indiana, have invented certain useful Improvements in Fence-Posts, of which the following is a specification, reference being had therein to the accompanying drawing.

- 10 The present invention has reference generally to improvements in that class of inventions known as metallic building structures and more particularly relates to an improved fence post.
- 15 The invention, as its primary aim and object, contemplates the provision of improved means mounted on the lower portion of the body of the post for reinforcing the base which is preferably formed of concrete, thus 20 insuring of an efficient engagement between the body of the post and the base.

More particularly, the present invention includes the provision of improved means formed on the outer edge of the body for 25 supporting the strips of reticulated material so that they may be arranged in a substantial wedge-like form and thereby be effectively anchored in the cementitious base.

As a further improvement, the present invention embraces the provision of novel 30 means for fastening wire to the body of the post, the means being capable of holding one or more strands of wire regardless of the angular disposition with respect to the body 35 of the post.

Among the other aims and objects of the present invention may be recited the provision of a device of the character mentioned with a view to compactness, and in which 40 the number of parts are few, the construction simple, the cost of production low and the efficiency high.

Other objects as well as the nature, characteristic features and scope of this invention will be more readily apparent from the following description taken in connection with the accompanying drawings and pointed out in the claim, forming a part 45 of this specification.

50 The preferred embodiment of this invention is clearly illustrated in the accompanying drawings, in which:—

Figure 1 is a front elevation of the invention.

55 Fig. 2 is a vertical section of the invention.

Fig. 3 is an enlarged sectional detail of the reinforcing strips in position.

Similar characters of reference are employed in all of the above described views, 60 to indicate corresponding parts.

Referring now, more particularly, to the accompanying drawings there is provided a fence post including a tubular metallic body 1 the lower edge of which is slit at uniformly spaced intervals while the portions adjacent the slits are bent outwardly and curved to provide flanges 2. As will be appreciated these flanges extend in opposite directions to each other and are arranged 65 in opposed pairs to assume a substantially cross like formation. A plurality of preferably four strips of reticulated material 3 are now provided and have their upper ends secured by suitable fastening means such 70 as transversely extending bolts 4 upon opposite sides of the lower portion of the post, and are extended outwardly in divergent relation with respect to each other, the lower ends being curved inwardly and upwardly 75 as indicated by the numeral 5 while the extreme outer terminals are connected in opposed relation to each other to the outer surface of the extreme lower portion of the body by suitable fastening devices such as 80 bolts 6. As will be appreciated the curved portions 5 have a similar configuration and rest upon the corresponding flanges 2 so as 85 to be supported thereby.

As intimated a cementitious base 7 is provided and it will be understood that this base is molded about the lower portion of the body 1 subsequent to the application of the reticulated strips 3, which, incidentally, serve to reinforce the body and owing to the 90 fact that they are arranged divergently to each other they constitute a substantial wedge and assist in the firm anchoring of the base on the body. The curved flanges 2 support the curved portions 5 of the strips 95 3 and prevent the strips from sagging and moving toward the post while the concrete base is being molded.

In order to provide suitable means for removably fastening pieces of wire or screen 105 wire, (not shown) to the post the upper portion of the body is provided with pairs of spaced openings 8 each pair of which have their forward ends arranged on an imaginary diagonal line with respect to the 110 upper portion of the body while the other ends are arranged in spaced relation to each

other in a plane parallel to the longitudinal axis of the body. U-shaped clips or staples 9 are now provided for engagement with the openings for fastening pieces of wire regardless of the angular disposition of the pieces of wire with respect to the body of the post. The arms 10 are arranged in spaced parallel relation with each other but are extended in opposite directions so that when their free ends are arranged in a vertical plane the intermediate portion will be positioned diagonally thereof. The direction assumed by the arms is corresponding to the positioning of the openings 8 so that the arms may be readily fitted therein to consequently arrange the intermediate portions of each of the clips diagonally of the body of the post as indicated in the drawings consequently enabling one or more wires being fastened to the body of the post regardless of the angular disposition thereof. Suitable fastening devices such as nuts 11 serve to removably clamp the clips in position.

In view of the foregoing description it is believed that a further detailed description of the operation of the invention is unnecessary. Likewise it is believed that the advantages of the invention will be readily apparent.

As many changes could be made in the above construction and many apparently widely different embodiments of this invention could be made without departing from the scope thereof, and it is intended that all matter contained in the above description or shown in the accompanying drawings

shall be interpreted as illustrative and not in a limited sense. It is also to be understood that the language used in the following claim is intended to cover all the generic and specific features of the invention herein described and all statements of the scope of the invention, which, as a matter of language might be said to fall therebetween. 45

Having thus fully described this invention, what is claimed as new and desired to be secured by Letters Patent, is:—

A fence post including a tubular body the lower edge of which is provided with a plurality of vertical slits, outwardly and upwardly curved pairs of opposed flanges formed on the lower end of the body and between the slits, a plurality of strips of reinforcing screening, means for securing the upper ends of the strip to the outer surface of the body, the main portions of the strips being extended downwardly in divergent relation with respect to each other to form a substantial wedge exteriorly of the body, the lower portions of the strips being curved inwardly and upwardly and intimately contacting with the upper surface of the adjacent correspondingly curved flanges so as to be braced and supported by the flanges, means for securing the lower terminals of the strips exteriorly of and against the outer surface of the body, and a cementitious base arranged about the lower portion of the body and anchored thereon and reinforced by the strips. 70

In testimony whereof I affix my signature.

CHARLES HENKEL.
